Fraenkel and Richard,
ATTORNEYS.

UNITED STATES PATENT OFFICE.

MILTON M. ADLER, OF NEWARK, NEW JERSEY.

PYROTECHNICAL DEVICE.

Application filed October 27, 1922. Serial No. 597,408.

To all whom it may concern:

Be it known that I, MILTON M. ADLER, a citizen of the United States, residing at Newark, in the county of Essex and State of New Jersey, have invented certain new and useful Improvements in Pyrotechnical Devices; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in pyrotechnical devices; and the invention has reference, more particularly, to an improved detonating fire-work or fire-cracker.

The invention has for its principal object to provide a novel construction of detonating fire-work or fire-cracker which is safe to handle, which will not fly apart when set off so as to endanger the eyes or person of the user, or entail the risk of igniting fires, and which is constructed to produce, when set off, a series or intermittent succession of detonations, rendering the same of pleasing and interesting effect, and providing a fire-work or fire-cracker which will operate for a comparatively long time after it is ignited.

Other objects of this invention, not at this time more particularly enumerated, will be clearly understood from the following detailed description of the same.

With the various objects of this invention in view, the same consists, primarily, in the novel detonating fire-work or fire-cracker hereinafter set forth; and, the invention consists, furthermore, in the novel arrangements and combinations of the several devices and parts, as well as in the details of the construction of the same, all of which will be hereinafter more fully described in the following specification, and then finally embodied in the claims appended thereto.

The invention is clearly illustrated in the accompanying drawings, in which:

Figure 1 is a perspective view of the complete fire-work or fire-cracker, showing one embodiment of this invention; Figure 2 is a vertical cross section through the same; Figure 3 is a plan view of a combustible carrier sheet upon which a plurality of pastilles or lozenges of pyrotechnical composition are mounted, and which is adapted to be wadded

or crumpled up and then inserted in the outer case of the fire-work device; and Figure 4 is an edge view of the paper sheet and its pastilles or lozenges of pyrotechnical composition. Figure 5 is a vertical cross section through the complete device, showing an alternative arrangement within the outer casing of the paper sheet and its pastilles or lozenges of pyrotechnical composition.

Similar characters of reference are employed in all of the hereinabove described views, to indicate corresponding parts.

Referring now to said drawings, the reference character 1 indicates an outer casing or box, the upper wall of which is provided with an opening 2. Said casing or box 1 is provided at its opposite ends with end-flaps 3 provided with tuck-flaps 4, whereby the ends of the casing or box are normally closed. Provided in said end-flaps 3 or at other points in the sides of the complete casing are a plurality of ventilating perforations 5, which permit access of air into the interior chamber 6 provided by the casing or box. The said casing or box is preferably made of comparatively heavy paper or light cardboard.

The reference character 7 indicates a combustible carrier sheet preferably made of thin paper, such as tissue paper, upon which are caused to adhere a plurality of pastilles or lozenges 8 consisting of a pyrotechnical composition adapted to produce detonations when ignited. It will, of course, be understood that there are many different pyrotechnical compositions known to those skilled in the art which, when ignited, will produce detonations, and consequently, in this respect I do not desire to limit myself to the use of any particular composition so characterized, although I prefer to employ a composition heretofore known and used to produce intermittent detonations, and which

comprises a mixture of gum-arabic, carbonate of mogulsium, white phosphorus, red ochre and potassium chlorate. The pastilles or lozenges 8 of pyrotechnical composition are arranged in a group, the members of which are suitably spaced apart. It is preferable to treat the paper or other carrier sheet 7 with some chemical adapted to insure continued combustion thereof once the same is ignited. A chemical such as saltpeter may be employed for such purpose, although I do not wish to be understood as confirming my

self to the use of that substance for the purpose indicated.

After the carrier sheet 7 with its group of spaced apart pastilles or lozenges of pyrotechnical composition 8 in adhering relation thereto is prepared, and the casing 1 is set up to receive the same, the said carrier sheet 7 is crumpled up and inserted through the opening 2 so as to be enclosed 10 within the interior of the casing 1. If desired one or more of the corners 7' of the carrier sheet 7 may be left protruding outwardly from the interior of the casing 1 through the opening 2, so as to provide an 15 exteriorly projecting fuse-like portion to be ignited when setting off the device, which arrangement is shown in Figures 1 and 2 of the drawings. If desired, however, instead of arranging the carrier sheet 20 7, the same may be crumpled up with the corners 7' enclosed within the casing, and the body of the sheet carrying the pastilles or lozenges 8 of pyrotechnical composition disclosed at the opening 2 of the casing and 25 thus exposed to the flame of a match, when the latter is applied at the opening 2 to ignite the carrier sheet, which arrangement is shown in Figure 5 of the drawings.

The carrier sheet 7 and its pastilles or lozenges 8 of pyrotechnical composition being enclosed in the casing in either manner above described, the device is ready for use. In operation, the carrier sheet 7 is ignited and burns, whereby the combustion thereof 30 in turn ignites the pastilles or lozenges 8, so that as the latter are thus set off a succession of intermittent explosions or detonations will occur, which will continue for a comparatively long time. Air to support 35 the combustion of the carrier sheet and the pastilles or lozenges of pyrotechnical composition will find its way into the interior of the casing through the ventilating perforations 5 provided in the sides of 40 the casing. The detonating material being enclosed within the casing 1 cannot fly about when set off, and the hollow interior of the casing tends to emphasize the reports or sound of the detonations. It will thus be 45 apparent that the device is unusually safe for children's amusement since there is little danger of scattering particles of fire or smoldering fragments burning the child, igniting its clothing, or objects in the vicinity 50 wherein the device is set off. Furthermore, owing to the spaced arrangement or separation of the members of the group of pastilles or lozenges of pyrotechnical composition 8 on the carrier sheet, the ignition 55 of the same is sure to be intermittent so that a succession of detonations similar to that produced by igniting a whole pack of old-fashioned fire-crackers is produced. The effect of a succession of intermittent detonations is increased when the particular com-

position above referred to is employed for the pastilles or lozenges, since it is characteristic of such composition that it burns slowly and produces intermittent detonations while burning, so that in addition to 70 the separate reports of the different individual pastilles or lozenges upon ignition thereof each such individual pastille or lozenge will of itself produce a plurality of intermittent reports. 75

I am aware that some changes may be made in the arrangements and combinations of the parts making up the device, as well as in the details of the construction and composition of said parts, without departing from the scope of this invention as above set forth, and as defined in the following claims. Hence, I do not limit myself to the exact arrangements and combinations of the various parts as described in 80 the above specification, nor do I confine myself to the exact details of the construction of the said parts as illustrated in the accompanying drawings. 85

I claim:—

1. A pyrotechnical device, comprising a casing adapted to provide a hollow enclosed interior, a combustible carrier sheet having a group of separated lozenges of detonating pyrotechnical composition secured thereto, 95 said combustible carrier sheet being crumpled up and enclosed within said casing, and said casing having an opening exposing said carrier sheet for ignition.

2. A pyrotechnical device, comprising a 100 casing adapted to provide a hollow enclosed interior, a combustible carrier sheet having a group of separated lozenges of detonating pyrotechnical composition secured thereto, said combustible carrier sheet being crumpled up and enclosed within said casing, 105 said casing having an opening exposing said carrier sheet for ignition, and the side walls of said casing having ventilating perforations to admit air into the interior of said 110 casing.

3. A pyrotechnical device, comprising a box-like casing having a comparatively large opening in its upper side, a paper carrier sheet having a plurality of spaced apart 115 bodies of pyrotechnical composition attached thereto adapted to detonate when ignited, said paper carrier sheet being enclosed within said casing and having portions thereof disclosed at the opening of 120 said casing so as to be exposed for ignition.

4. A pyrotechnical device, comprising a box-like casing having a comparatively large opening in its upper side, a paper carrier sheet having a plurality of spaced apart 125 bodies of pyrotechnical composition attached thereto adapted to detonate when ignited, said paper carrier sheet being enclosed within said casing and having portions thereof disclosed at the opening of 130

said casing so as to be exposed for ignition, and the side walls of said casing having ventilating perforations to admit air into the interior of said casing.

5 5. A pyrotechnical device, comprising an enclosing casing within which is disposed a combustible carrier means treated with a pyrotechnical composition adapted to detonate when ignited.

10 6. A pyrotechnical device, comprising an enclosing casing within which is disposed a combustible carrier means treated with a pyrotechnical composition adapted to detonate when ignited, and said casing having 15 an opening exposing said carrier means for ignition.

7. A pyrotechnical device, comprising an enclosing casing within which is disposed a combustible carrier means treated with a 20 pyrotechnical composition adapted to detonate when ignited, said casing having an opening exposing said carrier means for ignition, and said casing being further provided in its side walls with ventilating 25 perforations.

8. A pyrotechnical device, comprising an enclosing casing within which is disposed a combustible carrier means, and said carrier means having attached thereto a plu-

rality of pastilles formed of a pyrotechnical composition adapted to detonate when ignited.

9. A pyrotechnical device, comprising an enclosing casing within which is disposed a combustible carrier means, said carrier means having attached thereto a plurality of pastilles formed of a pyrotechnical composition adapted to detonate when ignited, and said casing having an opening exposing 35 said carrier means for ignition. 40

10. A pyrotechnical device, comprising an enclosing casing within which is disposed a combustible carrier means, said carrier means having attached thereto a plurality of pastilles formed of a pyrotechnical composition adapted to detonate when ignited, said casing having an opening exposing said carrier means for ignition, and said casing being further provided in its side walls 45 with ventilating perforations. 50

In testimony, that I claim the invention set forth above I have hereunto set my hand this 14th day of October 1922.

MILTON M. ADLER.
